UNITED STATES PATENT OFFICE.

WILLIAM I. MACOMBER, OF PROVIDENCE, RHODE ISLAND.

CHAIN BRACELET.

SPECIFICATION forming part of Letters Patent No. 315,525, dated April 14, 1885.

Application filed October 9, 1884. (No model.)

To all whom it may concern:

Be it known that I, WILLIAM I. MACOMBER, of Providence, in the State of Rhode Island, have invented an Improvement in Chain Bracelets, of which the following is a specification.

The nature of my invention consists in an improved box-clasp for a chain bracelet, by means of which the bracelet is made adjustable to the wrist of the wearer, as hereinafter set forth.

Figure 1 is a top view of a chain bracelet, showing the bracelet in an unclasped condition, with a portion of the hinged cover broken away, in order to more fully show the form of the locking-springs. Fig. 2 is a partial section of the bracelet taken in the line xx of Fig. 1. Fig. 3 is an enlarged section showing the several parts in their locked condition. Fig. 4 is a transverse section taken in the line xx of Fig. 3.

In the accompanying drawings, A is the ordinary roller-chain secured at its end a to the rear of the ornamental box B, which is provided with a cover, b, hinged to the box at the point c. At the under side of the cover b are secured the downwardly-projecting hooks $d d$, which, when the cover b is closed upon the box, serve to catch under the springs C C, and thus hold the cover firmly upon the box; and the cover may be thrown back, as shown in Figs. 1 and 2, by first forcing the springs C C inward, by means of pressure upon the ends of the laterally-projecting studs $e e$, which project through suitable openings, f, made in the side of the box. The forward end of the box is cut away and provided with a catch-piece, g, having upright pins $h h$, adapted to enter the spaces between the links of the chain, the hinged cover b, closing downward in the direction of the chain, and provided at its under side with the opposite hooks, $d d$, the oppositely-arranged springs C C, provided with a projecting stud, e, and adapted for locking engagement with the hooks $d d$, which are held between the springs C C and the sides of the box, substantially as described.

The bracelet being first placed upon the wrist of the wearer, the free end j of the chain is brought forward to the proper distance within the box B and caught over the pins h ,

which enter the spaces between the links. The cover b is then to be brought to its closed position, the thinned end of the hooks d entering the space k , formed between the springs C and the inner sides of the box, and when the cover is completely closed upon the box the hooks d will catch under the lower edge of the springs, as shown in Fig. 4, in which position the cover will be firmly held, so as to lock the chain upon the pins h until the hooks d are released from the springs by the inward movement of the projecting studs e , which form a lateral continuation of the free end of the spring.

I am aware that a hinged fastening for bracelet chains is shown and described in Patent of the United States No. 283,333, having a series of teeth in the base, and a cover-plate provided with a spring-catch device adapted to engage the base-plate and hold the teeth thereof in engagement with the chain. I therefore make no general claim to such a fastening device for bracelets, but only to the improved construction and arrangement of the springs and catches for locking the hinged cover of the same.

I therefore claim as my invention—

In a bracelet, the combination of the chain A, the box B, secured to one end of the chain and provided at its forward end with the catch-piece g, having upright pins $h h$, adapted to enter the spaces between the links of the chain, the hinged cover b, closing downward in the direction of the chain, and provided at its under side with the opposite hooks, $d d$, the oppositely-arranged springs C C, provided with a projecting stud, e, and adapted for locking engagement with the hooks $d d$, which are held between the springs C C and the sides of the box, substantially as described.

WILLIAM I. MACOMBER.
